PACKAGING MACHINE

Sidney G. Fisher, Charleston, S. C.

Application December 29, 1952, Serial No. 328,433

1 Claim. (Cl. 53—215)

This invention relates to a packaging machine and more particularly to a device especially adapted to package rags or any other fibrous material such as cotton, silk, paper, jute, wood, rayon and other synthetic fibers, hemp and the like and the term rags as used throughout the specification and claim is not to be considered any limitation whatsoever on the type of material to be packaged.

This invention includes the use of a platen on which an apron is loosely positioned. There is provided a roller which passes over the platen and beneath the apron, catching in the folds of the apron a predetermined amount of rags to compress such rags forming a cylindrical package thereof. The concept of this invention features the use of means for adjusting the height of the roller above the platen and also for adjusting the size of the fold in the apron.

Still further objects of the invention reside in the provision of a packaging machine which is strong and durable, capable of packaging rags at a relatively high rate, which employs a minimum number of parts so as to enable even unskilled workers to operate the machine satisfactorily to produce packages of rags which may be widely distributed.

Many industrial plants, hotels, apartment houses, machine shops, garages, etc., require wiping and cleaning rags for various uses. Heretofore, these businesses purchased large bales or bundles of rags which when once broken tend to cause the rapid use and exhaustion of the presently available supply of rags. This invention enables rags to be distributed in relatively small packages which may then be packed with a predetermined number of other packages in a suitable carton for delivery to the user. Further the individual packages may be sold to the small consumer or householder.

These, together with the various ancillary objects of the invention which will become apparent as the following description proceeds, are attained by this packaging machine, a preferred embodiment of which has been illustrated in the accompanying drawings, by way of example only, wherein:

Figure 1 is a perspective view of a package of rags formed on the machine comprising the present invention;

Figure 2 is a side elevational view of the rag packaging machine;

Figure 3 is a top plan view of the invention showing the construction of the roller adjusting means.

Figure 4 is a vertical sectional view as taken along the plane of the longitudinal axis of the device; and,

Figure 5 is a sectional detail view in an enlarged scale of the roller adjusting means.

With continuing reference to the accompanying drawings wherein like reference numerals designate similar parts throughout the various views, it will be seen that the rag packaging machine comprising the present invention includes an angle iron base framework 10 which is preferably rectangular in shape. A platen 12 having an arcuate configuration is supported medial the ends of

2

the framework 10 by means of suitable frame members 14 of desired configuration. Polygonal shaped side plates 16 and 18 are secured to the sides of the framework 10. Vertically extending apron supporting studs 20 and 22 are secured to the framework 10 and carry a transverse rod 24 to which an apron 26 is secured. The apron 26 is formed from a suitable resilient and flexible material such as a rubber impregnated and coated cloth and overlies the platen 12. The other end of the apron is provided with a hem 32 forming a loop 34 for reception of a rod 36 which is adapted to be inserted in the loop 34. The rod 36 is supported by spaced upwardly extending apron studs 38 and 40, both of which are provided with aligned apertures 42 therethrough. In order to determine the effective operating length of the apron 26, the rod 36 is secured within selected apertures 42 in the studs 38 and 40, thus determining the amount of material that is available to form a fold portion 44 in said apron.

Pivottally mounted on mounting plates 46 and 48 attached to the framework 10 by means of shaft 52 are a pair of handle sections 54 and 56 which are joined together as at 58 and then diverge in order that a hand grip member 60 may be supported therebetween and suitably journaled therein. Attached to the handle section 56 is a spaced pair of brackets 62 and 64 in which a threaded shaft or member 66 is journaled for rotation. A knurled knob 68 is attached to the end 70 of the member 66 extending through the bracket 64. Carried by and threadedly engaged with the member 66 is an internally threaded support block 72. Carried by the spaced pair of brackets 74 and 76 which are attached to the handle section 64 and journaled therein is a threaded member 78 actuated by a knurled knob 80. A support block 82 is threadedly engaged on the threaded member 78. Secured in the support blocks 72 and 82 and extending therebetween is a shaft 84 to which there is attached the inner races 86 of the cluster of roller bearings 88. The outer race 90 is attached to a roller 92 of cylindrical configuration. Depending from the handle sections 54 and 56 and attached to the inner surface thereof and extending rearwardly of the roller 92 are roller end plates 94 and 96. In order to form a package of rags such as indicated by reference numeral 100 in Figure 1, the packaging machine employs the following mode of operation. An initial and weighed charge of rags is positioned within the fold 44 in the apron 26. Then, the handle sections 54 and 56 are actuated so as to contract and compress the rags 102 in the manner as can be seen best in Figure

4. No slack then remains in the apron 26 and the fold 44 is entirely supported by the platen 12. At this point, a covering sheet of paper 104 is inserted on the apron covered roller 92. Then, the handle sections 54 and 56 are pulled all the way over the platen 12 delivering the completely formed package. The sheet of paper 104 is provided with a gummed, tacky, adhesive edge prior to insertion underneath the roller. A pull cord 106 may be bound with the covering paper 104 in order to enable the swift removable of such covering. When the rags are inserted in the fold 44 as shown in Figure 2 the side plates 16 and 18 prevent any of the rags from falling away from the sides of the apron. After the apron has become supported by the platen 12, the side plates 94 and 96 prevent the rags from being squeezed out from the sides of the apron and aid in the formation of a tubular cylindrical package.

Since from the foregoing, the construction and advantages of this packaging machine are readily apparent, further description is believed to be unnecessary.

However, since numerous modifications will readily occur to those skilled in the art after a consideration of the foregoing specification and accompanying drawings, it is

not intended to limit the invention to the precise embodiment shown and described, but all suitable modifications and equivalents may be readily resorted to that fall within the scope of the appended claim.

What is claimed as new is as follows:

A rag packaging machine comprising a support platform having pairs of upwardly extending apron-support stud members secured at opposite end portions of said frame, an upwardly disposed arcuate platen having an upper convex surface supported intermediate the ends of said support frame and terminating at opposite edges between said apron-support stud members, side plate members secured between opposite pairs of aligned upwardly extending stud support members on opposite ends of said frame, a flexible apron extending between said side plates in overlying relationship on said platen, said apron having one end secured to opposite upper end portions of one pair of stud members at one end of said frame, the other pair of stud members at the other end of said frame including a plurality of vertically disposed aligned adjusting apertures, the other end of said apron being adjustably secured between the aligned apertures of the other pair of stud members and defining a variable upwardly opening fold portion in said apron for receiving rags to be packaged for forming variable sized bundles of packaged rags, the adjustable end of said apron including a hem portion along the edge thereof, a rod element extending through said hem portion in the apron beyond the opposite edges thereof, said rod being insertable into oppositely disposed apertures in the other pair of stud members, a pair of upwardly extending elongated and opposed handle sections including a handle portion between upper end portions thereof and being pivotally connected at lower end portions at opposite side portions adjacent said frame, the pivotal connection thereof being equidistant from the arcuate upper surface of the platen, the support shaft extending between said handle sections in parallel relationship transversely beneath the apron, end plates secured on said handle sections in abutting relationship to the adjacent edges of the apron closing the

ends of the fold portion defined therein when the handle sections are rotated about the pivotal connection thereof, a packaging roller journaled on said shaft and circumferentially engageable beneath said apron between the 5 fold and vertically adjustable end portions thereof for closing the fold portion, said roller including closed ends having an annular recess in axial alignment with the longitudinal axis of the roller and shaft, a bearing race disposed within said recesses and engageable between said 10 roller and shaft for reducing the frictional resistance to rotation between said shaft and roller, said fold portion cooperating with the side plate members for defining the hopper for receiving rags to be formed in a package, the fold portion being movable across the upper arcuate 15 surface of said platen for forming a package with a suitable cover sheet juxtaposed on the upper surface of said platen, means on said handle for adjusting the shaft and roller toward and away from the pivotal end of said handle sections for varying the peripheral distance of the 20 roller on the upper surface of the platen when the handle sections are rotated about their pivotal connection, said means including a pair of spaced brackets disposed on opposite sides of an aperture portion extending through each of said handle sections, threaded members journaled 25 in said brackets in parallel relationship to the handle sections, means on the ends of the threaded members for rotating the same, ends of the support shaft extending through the aperture portions in said handle sections and secured to support blocks, the threaded members extending 30 through the support blocks transversely of said support shaft enabling rotation of the threaded members to adjust the roller longitudinally relative to the handle sections.
